DESIGN FOR AN ARM-REST FOR BARBERS' CHAIRS.

Design No. 18,526, dated August 14, 1888.

UNITED STATES PATENT OFFICE.

THEODORE A. KOCHS, OF CHICAGO, ILLINOIS.

DESIGN FOR AN ARM-REST FOR BARBERS' CHAIRS.

SPECIFICATION forming part of Design No. 18,526, dated August 14, 1888.

Application filed June 15, 1888. Serial No. 277,265. Term of patent 7 years.

To all whom it may concern:

Be it known that I, THEODORE A. KOCHS, a citizen of the United States of America, residing at Chicago, in the county of Cook and State 5 of Illinois, have invented and produced a new and original Design for Arm-Rests for Barbers' Chairs, of which the following is a specification, reference being had therein to the accompanying illustration.

10 The illustration represents a perspective view of a barber's chair having my newly-designed arm-rest.

15 The leading feature of my design consists in a dragon's head with protruding tongue, forming the end of the arm-rest and the connection with the front standard thereof.

19 A is the arm-rest, and B the front standard of each arm-rest.

20 C is the representation of a dragon's head with open mouth and with his tongue protruding, the tip of which tongue being coiled. This dragon's head is made to project from the connecting-corner of the arm-rest and front standard, thus forming a forward continuation of the arm-rest, while the coiled tip of the dragon's tongue rests upon the outwardly-curved upper portion of the arm-rest standard B.

I do not claim, broadly, the design of a dragon's head as applied to chairs, nor do I claim such design when forming part of the front standard or support for the arm-rest; but

What I do claim is—

The design for an arm-rest, consisting of the representation of a dragon's head, the neck to which is a forward continuation of the arm-rest bar, and the rearwardly-coiled protruding tongue of the dragon resting upon the rearwardly-curved portion of the front supporting-standard of the arm-rest, substantially as described and shown.

In testimony whereof I affix my signature in presence of two witnesses.

THEODORE A. KOCHS.
